UNITED STATES PATENT OFFICE.

HERMAN C. KUPPER, OF NEW YORK, N. Y.

DESIGN FOR A TEAPOT OR SIMILAR ARTICLE.

42,565.

Specification for Design.

Patented May 28, 1912.

Application filed December 9, 1910. Serial No. 596,556. Term of patent 7 years.

To all whom it may concern:

Be it known that I, HERMAN C. KUPPER, a citizen of the Republic of Switzerland, and a resident of New York city, in the county of New York and State of New York, have invented a certain new, original, and ornamental Design for a Teapot or Similar Article, of which the following is a specification.

In the accompanying drawing, Figure 1 is a perspective showing the design of the tea pot. Fig. 2 is a plan of the same.

I claim—

The ornamental design for a tea pot or similar article as shown.

HERMAN C. KUPPER.

Witnesses:

E. J. CONRAD,

E. T. GREINER.
